UNITED STATES PATENT OFFICE.

CLINTON L. WALKER, OF PIEDMONT, CALIFORNIA.

PNEUMATIC STARTING MECHANISM FOR AUTOMOBILES.

1,250,733.

Specification of Letters Patent. Patented Dec. 18, 1917.

Application filed September 18, 1916. Serial No. 120,671.

To all whom it may concern:

Be it known that I, CLINTON L. WALKER, a citizen of the United States, residing at Piedmont, in the county of Alameda and 5 State of California, have invented new and useful Improvements in Pneumatic Starting Mechanism for Automobiles, of which the following is a specification.

This invention relates to pneumatic starters and pumps for use in starting internal combustion engines, and has for its object to 10 simplify and improve the construction and operation thereof.

Although not limited in use to any particular type of automobile, pneumatic starters find their greatest use as an attachment for Ford automobiles, and consequently I have so designed the present mechanism as 15 to adapt it readily to this type of automobile.

20 In producing this invention, I have had in mind the accomplishment of several desiderata. One is to combine a starter and pump in one compact unit and to locate the same within the hood of the engine, to thereby 25 conceal it, leaving the hand crank in place at the front of the radiator. Necessarily the attachment has to be located at one side of the engine under such circumstances, and a driving belt or chain extended from the 30 starter shaft to the engine shaft. I provide a novel and adjustable connection for securing the combined starter and pump in place 35 on the engine at one side thereof, and employ a novel form of pump connection between the engine shaft and the chain drive leading 40 to the starter shaft, whereby the chain drive may be disconnected when not in use, and allowed to remain idle. I make use of a 45 novel form of cylinder and piston for the starter in order to obtain the greatest efficiency in the limited space permitted. Novel and advantageous control and relief valve mechanism for the starter are also provided, and an advantageous arrangement is made 50 use of in connection with the check valve between the pump and storage tank whereby to obtain an oil seal around the valve. Preferably I employ a single shaft for both 55 starter and pump, and therefore am enabled to make use of one driving connection between this shaft and the engine shaft for

starting the engine and for operating the pump.

Other novel and important features will 55 become apparent upon a further understanding of the invention.

In the accompanying drawings, Figure 1 shows a side elevation of the front portion of an automobile embodying my invention, certain parts being broken away for the sake 60 of clearance.

Fig. 2 shows an end view of the supporting mechanism for the starter and pump, 65 detachably connectible with an automobile engine.

Fig. 3 shows a side elevation of the same.

Fig. 4 shows a vertical longitudinal sectional view through the pump illustrating the starter in end elevation in the background.

Fig. 5 shows a side elevation of the combined starter and pump.

Fig. 6 shows a longitudinal central sectional view through the starter and pump.

Fig. 7 shows a transverse sectional view 75 through the starter.

Fig. 8 shows a circumferential view through the spring housing of the starter.

Fig. 9 shows a detailed sectional view of the starter shaft illustrating the ratchet 80 clutch mechanism.

Fig. 10 shows a detailed sectional view of the starter illustrating a modified form of connection between the piston and sleeve.

Fig. 11 shows a detailed sectional view of 85 the relief and check valve mechanism employed between the pump and storage tank.

Fig. 12 shows a detailed sectional view of the clutch connection on the engine shaft for receiving the driving chain of the starter. 90

Figs. 13 to 16 inclusive show detailed views of other parts of said clutch mechanism.

Fig. 17 is a fragmentary transverse section through a slightly modified form of a starter in which the head is secured between 95 the flanged ends of the cylindrical sheet.

Fig. 18 is a fragmentary elevation of the modified starter.

In Fig. 1 I show a portion of an automobile including a radiator 10 and internal 100 combustion engine 11.

The starter is of the oscillating piston

type as indicated generally at 12, the pump is of the type shown and described in my co-pending application Serial No. 46,057 filed Aug. 18th, 1915, and is indicated generally at 13, and these two are combined and detachably mounted upon one side of the engine.

The supports for the starter and pump comprise a frame 14, illustrated in end elevation in Fig. 2, and in side elevation in Fig. 3.

The frame has lugs or arms 15, preferably two above and one below, detachably secured to the side of the motor by means of 15 bolts or screws 16. The arms 15 are so positioned that the upper ones register with the position of the cylinder head bolts, and the lower one registers with one of the bolts used for connecting the cylinders and upper 20 half of the crank case in a Ford motor.

The frame 14 includes end pieces 17, having vertical slots 18 in which are slidably mounted blocks 19 and 19^a connected to the starter and pump respectively, and adjustably supported by screws or bolts 20. By manipulating the screws 20, the position of the starter and pump may be adjusted vertically for the purpose of tensioning the driving chain as will hereinafter appear.

30 The starter comprises a casing 21 formed of a single sheet rolled into cylindrical form, with its ends 22 provided with flanges adapted to be secured together by means of screws or other clamping devices. Disk shaped members 23 and 23^a form the end walls of the starter and are inserted in grooves formed in the casing and securely held therein when the ends 22 are clamped together.

40 The end wall 23^a it will be noted also forms one side of the pump 13, and is connected integrally therewith. A common shaft 24 is provided for both starter and pump, and is journaled at its ends in bushings 25 mounted in the end pieces 19 and 19^a. The starter has a piston 26 carried by a sleeve or hollow shaft 27, the latter rotatably supported in hubs 28 formed on the end walls of the starter. Coöperating with the 50 piston is a longitudinally extending stationary head 29, which as shown in Fig. 7, is fitted in radial slots or grooves formed in the end walls of the cylinder, and carries a leather packing 30 on its front face, having its ends engaging the walls of the cylinder and turned toward the high pressure side. Wood fillers 31 are bolted to either side of the head 29 and form bumpers for absorbing the shocks of the piston. The 55 piston is also shown as supplied with a bumper 32 and a packing member 33. A ring 34 of soft rubber is preferably mounted in the filler 32 for expanding the ends of the packing 33. If desired, stay bolts 35 60 may be extended longitudinally through the

blocks 31 to secure the head in place within the cylinder.

A modified arrangement for attaching the piston to the sleeve is shown in Fig. 10, and comprises a series of short lengths of steel 70 rods 36 screw fitted on to the sleeve, each pair forming a support for the head of a bolt 37 secured to the piston. This is a strong and extremely inexpensive connection, no special form of tool being required to construct it. 75

The clutch mechanism is interposed between the sleeve 27 and shaft 24 and comprises a fixed member 38 keyed to the shaft and a shiftable member 39 coarse threaded to the sleeve 27 and moved longitudinally 80 by a screw feed action. These clutch members have their coöperating faces provided with ratchet teeth. A drag spring 40 as shown in Fig. 9 is attached to a bushing 41 which latter is fixed upon a bearing ring 42 85 removably secured to the head 23^a. This spring presses at its free end against the inside shoulder on the member 39, and forms a yielding and frictional connection between the screw feed clutch member and a stationary part of the cylinder. Therefore when the piston 26 is initially moved, the said clutch member will be restrained in its rotative movement, thereby allowing the threads on the sleeve 27 to feed the member 90 39 forwardly into engagement with the teeth on the member 38, whereby to turn the shaft 24.

The piston is automatically returned by a clock spring 43 carried within an annular 100 flange 44 on the exterior of the end-wall 23 and secured at its outer end thereto. The inner end of the spring is secured to a hub 45 which is screw threaded to the adjacent end of the sleeve 27. The bearing block 19 105 is detachably secured to the flange 44 and forms therewith an inclosed housing for the spring. The outer end of the spring is hooked in an opening formed in the peripheral flange of the bearing block member 19 110 so that the latter may be removed from its vertical guide and turned over to vary the tension of said spring. A modified form of return spring is shown in connection with Fig. 10 and comprises a contractile coil 115 spring 46, on the exterior of the housing, to which is attached a rope 47 wound upon a drum 48, the latter formed upon the hub 45.

The forward end of the shaft 24 has fixed 120 upon it a sprocket wheel 49 carrying a chain 50 running to a sprocket wheel 51 on the crank shaft 52 of the motor. I so arrange the connections between the chain and crank shaft as to utilize the parts of a Ford motor 125 to the greatest possible extent. As will be seen in Fig. 12, I provide an extension 53 for the crank shaft, and connect it thereto by means of a cap 54 secured by pins 55, the latter already being in place on the crank 130

shaft for connecting the fan drive pulley. The fan drive pulley in its present form will consist of a shell 56 fitting over the cap 54 and held in place also by pins 55. A 5 novel clutch mechanism is interposed between the sprocket wheel 51 and the crank shaft extension and comprises a grooved and 10 slideable member 57 loose on the extension 53 and carrying a plurality of pins 58 passing through openings 59 in the sprocket wheel, and entering sockets formed in the side face of the cap 54 (see Figs. 12-16 inclusive). Any suitable shifting mechanism 15 may be provided for the slideable member 57, and the engagement should be made just as the engine is "dying" so as to be in position for use in re-starting.

The clutch pins 60 to receive the usual hand crank 61 will be carried on the outer 20 end of the extension 53. It will be seen that this arrangement does not disturb the alignment of the driving and driven sprocket wheels of the chain drive, and has advantages over frictional clutch devices in 25 economy of space and construction. The shiftable member 57 is preferably provided with 8 pins and seven of said pins might be broken off and the clutch would still hold with the one remaining.

30 The operative connections for the starter and pump include a supply tank 62 connected by a pipe 63 with the exhaust valve of the air pump. Included in the pipe connections 63 are stand pipes 64 and 65 carrying respectively a relief valve 66 and a check valve 67. As shown in Fig. 11 said stand pipes are of a somewhat enlarged diameter and occupy a vertical position so that oil which leaks from the pump 13 will be carried by the air through the pipe 63 and be trapped in said stand pipes above the valves 66 and 67, thereby forming oil seals for said valves to prevent leakage.

From the supply tank 62 a pipe connection 45 68 is extended to the starter 12 and opens into the cylinder at a point between the stationary head and piston. The control valve for the starter may be located adjacent the tank or on the starter. In Fig. 5 I 50 show it on the starter and it preferably comprises a casing 69 having a removable cover 70 and inlet and discharge opening 71 and 72 respectively. The control valve has a double seat comprising a piston 73 fitted in 55 a restricted passage way in the casing, and a flanged head 74 with V shaped grooves on its under surface adapted to seat upon a fabric ring 75. A spring 76 presses the valve into closed position. A tubular extension 77 on the valve passes through the casing 69 and carries on its outer end a relief valve 78 provided with a beveled head 79 to seat against the open end of the tubular extension. The tubular extension 80 65 communicates with the outlet chamber 72 of the

valve casing through apertures 80. For operating the control and relief valves I provide a lever 81 pivoted at 82 to the valve casing and having a foot extension 83 underlying the head 79 of the relief valve and the 70 extension 77 of the controlling valve. The relief valve is unseated and rests upon the extension 83 when the lever is released, whereas the control valve is normally seated by the pressure of the spring 76. A pull 75 upon the lever 81 will first cause the relief valve to be closed and thereafter the control valve to be raised allowing air from the tank 62 to rush into the starting cylinder and move the piston one revolution. When 80 the lever 81 is released the control valve is seated by the spring 76 and the relief valve drops back to open position by gravity or otherwise and allows the air present in the 85 starter to be exhausted.

The construction of the flanged head 74 and fabric ring 75 is such as to permit the use of an oil seal therefor, after the manner of the seals described in connection with Fig. 11. In Fig. 1, I show the control and 90 relief valves and operating mechanism therefor, arranged adjacent the tank 62, the construction and operation being the same as that already described.

The pump in its essentials comprises a 95 chamber 84 on either side of which is a cylinder 85 in alignment with each other and each fitted with a piston 86, the pistons being operated by an eccentric disk 87 mounted upon a squared portion of the shaft 24. 100 By combining the pump and starter in one unit and mounting both on a single shaft, I am enabled to simplify the driving connections with the crank shaft. The pump may be operated while the engine is running by 105 throwing the clutch member 57 into engagement, and by reason of the ratchet clutch between the sleeve 27 and shaft 24, the starter piston 26 will remain idle. When sufficient air has been pumped into the tank 110 62, the clutch member 57 is released and the chain 50 and its sprocket wheels will remain idle until used again for starting the motor.

Various changes in the construction and arrangement of the several parts herein 115 shown and described may be made, without departing from the spirit of my invention as disclosed in the appended claims.

By splining the clutch member 38 to the shaft 24 and mounting the eccentric disk 87 on a squared portion thereof, the said shaft is capable of longitudinal adjustment in its bearings, to permit the alignment of the sprocket wheels of the driving chain 50. Between the ends of the shaft and the blocks 120 19 and 19^a, I interpose removable washers 87^a which may be transposed from one end to the other in order to effect the longitudinal adjustment.

As shown in Figs. 17 and 18, the flanged 130

ends 22 of the cylinder may have washers or spacers 22^a interposed between them where the bolts or fasteners pass through, leaving the interior of the cylinder on the 5 low pressure side of the head 29 in communication with the atmosphere; thus when the piston is moved to the limit of its power stroke, there is no tendency for the air to be compressed ahead of it, and also on the return stroke the tendency of a vacuum to be 10 created is overcome.

Also as shown in said modification, the head 26 may be extended between the spaced ends 22 and receive support therefrom, thus 15 doing away with the necessity for stay rods or other supports.

Having thus described my invention, what I claim and desire to secure by Letters Patent is:—

wardly into opposing flanges, means adjustably connecting the flanges, said cylinder being formed with a seat adjacent each end, a head engaged in each seat and held therein by tightening upon said flange connecting means, each head having a hub extension, a sleeve journaled in the hubs, a piston carried by the sleeve within the cylinder, a shaft passing through the sleeve, a drive gear fixed on the shaft, a clutch part fixed on the shaft within the sleeve, a co-operating clutch part threaded interiorly of the sleeve for advancing toward and retracting from the fixed clutch part, and a drag spring interposed between the second clutch part and the shaft. 65 70 75 80

5. In a pneumatic starting mechanism, in combination a cylinder having its body formed of a single sheet rolled into circular form with the ends of said sheet turned outwardly into opposing flanges, means adjustably connecting the flanges, said cylinder being formed with a seat adjacent each end, a head engaged in each seat and held therein by tightening upon said flange connecting means, each head having a hub extension, a sleeve journaled in the hubs, a piston carried by the sleeve within the cylinder, a shaft passing through the sleeve and extending therefrom at its ends, a connection between the shaft and sleeve, and adjustable bearings for the projecting ends of the shaft. 95

6. In a pneumatic starting mechanism, in combination, a cylinder having its body formed of a single sheet rolled into circular form with the ends of said sheet turned outwardly into opposing flanges, means adjustably connecting the flanges, said cylinder being formed with a seat adjacent each end, a head engaged in each seat and held therein by tightening upon said flange connecting means, each head having a hub extension, a sleeve journaled in the hubs, a piston carried by the sleeve within the cylinder, a shaft passing through the sleeve, means releasably connecting the sleeve to the shaft, a hub extending from the sleeve through the hub extension of the adjacent head, and spring means secured to the hub exterior of the cylinder for returning the piston to its normal position. 100 105 110 115

7. A pneumatic starter and pump having a shaft common to both, a support for said starter and pump adapted to be secured to one side of an internal combustion engine, a chain drive for the shaft adapted to connect the latter to the engine shaft, and means by which said first shaft may be disposed at longitudinally fixed adjustments to permit alinement of the chain driving connections. 120 125

- 126 8. In a pneumatic starter, in combination, a cylinder, a shaft longitudinally adjustable therein, a hollow shaft arranged within the

5 cylinder and about the first shaft, a piston carried by the hollow shaft within the cylinder, and a drag spring interposed between the two shafts for frictionally connecting the same on rotary movement of one of said shafts.

9. A pneumatic starter comprising a cylindrical body portion formed of one piece and having flanged longitudinally extending 10 ends detachably connected together and end-walls received in grooves in said body portion and held therein by the clamping action of said body portion.

10. A pneumatic starter comprising a cylindrical body portion formed of one piece and having flanged longitudinally extending ends detachably connected together, end-walls received in grooves in said body portion and held therein by the clamping action 20 of said body portion, a stationary head in said cylinder extending radially, a shaft extending longitudinally through the cylinder, a sleeve on said shaft, a piston fixed upon said sleeve, and connecting means interposed 25 between said sleeve and shaft.

11. A pneumatic starter comprising a cylindrical body portion formed of one piece and having flanged longitudinally extending ends detachably connected together, end-walls received in grooves in said body portion and held therein by the clamping action of said body portion, a stationary head in said cylinder extending radially, a shaft extending longitudinally through the cylinder, a sleeve on said shaft, a piston fixed upon said sleeve, and means interposed 35 between said sleeve and shaft for connecting the two, said means comprising a screw feed member on one end of the sleeve, and a 40 coöperating member fixed upon the shaft.

12. A pneumatic starter comprising a cylindrical body portion formed of one piece and having flanged longitudinally extending ends detachably connected together, end-walls received in grooves in said body portion and held therein by the clamping action of said body portion, and a pump 45 formed integrally with one end-wall of said starter.

50 13. In a pneumatic starting mechanism, in combination, a cylinder having its body formed of a single sheet rolled into circular form with the ends of said sheet turned outwardly into opposing flanges, means adjustably connecting the flanges, said cylinder being formed with a seat adjacent each end, a head engaged in each seat and held therein by tightening upon said flange connecting means, each head having a hub extension, a 55 sleeve journaled in the hubs, a piston carried by the sleeve within the cylinder, a shaft passing through the sleeve, one head having an exterior annular flange, bearings for the shaft one of which is formed with a wall

65 having an annular flange telescopically related to the head flange, and forming therewith a housing, and means arranged in the housing thus formed for returning the piston to normal position.

14. In a pneumatic starting mechanism, 70 in combination, a cylinder having its body formed of a single sheet rolled into circular form with the ends of said sheet turned outwardly into opposing flanges, means adjustably connecting the flanges, said cylinder 75 being formed with a seat adjacent each end, a head engaged in each seat and held therein by tightening upon said flange connecting means, each head having a hub extension, a sleeve journaled in the hubs, a piston carried 80 by the sleeve within the cylinder, a shaft passing through the sleeve, a clutch part interposed between the sleeve and shaft and slidably connected to one, a coöperating clutch part threadedly connected to the other 85 of said two last named elements for advancement toward and retraction from the first clutch part, a hub fixed on the sleeve in the path of the slideable clutch part and extending through the hub extension of the adjacent head, and means connected with the hub for returning the piston to normal position.

15. In a pneumatic starter, in combination, a cylinder, a shaft longitudinally adjustable therein, a hollow shaft arranged within the cylinder and about the first shaft, a piston carried by the hollow shaft within the cylinder, a drag spring interposed between the two shafts for clutching the same 100 together upon rotation of the hollow shaft in one direction only, and means for returning the hollow shaft to normal position.

16. In a pneumatic starting mechanism, in combination, a cylinder having removable 105 heads each formed with a center bearing, a piston rotatably supported within the cylinder and in the bearings, means for returning the piston to normal position, a housing for said means carried by one head, a pump 110 having its casing carried by the other head, and a shaft extending through the cylinder, housing and pump casing for operating the pump and being operated by the piston.

115 17. In a pneumatic starting mechanism, in combination, a cylinder having removable heads each formed with a center bearing, a piston rotatably supported within the cylinder and in the bearings, means for returning the piston to normal position, a housing for said means carried by one head, a pump having its casing carried by the other head, a shaft extending through the cylinder, housing, and pump casing for operating the 120 pump and being operated by the piston, shaft bearings carried by the housing and pump casing, a supporting frame having 125

guideways in which the shaft bearings are slidably arranged, and means for adjusting the shaft bearings in the guideways of the frame.

5 18. In an oscillatory pneumatic starter, in combination, a cylinder having its body formed of a single sheet rolled into circular form, with the ends of said sheet connected together along their longitudinal edges and

10 spaced apart to permit free communication with the atmosphere, a head arranged within the cylinder at one side of said spaced ends, and a piston movable in the cylinder and having its low pressure side exposed 15 toward said spaced ends.

19. In an oscillatory pneumatic starter, in combination, a cylinder, a shaft extending therethrough, bearings for said shaft whereby to support the cylinder, a driving

20 gear fixed to one end of said shaft for operative connection with an engine, a sleeve on said shaft within the cylinder, a friction clutch between the sleeve and shaft adapted to engage the latter at any point throughout

25 its length and thereby permit the shaft to be moved longitudinally relative to the cylinder whereby to align the driving gear thereon with respect to a gear on the engine shaft, and a piston fixed to the sleeve for 30 operation in the cylinder.

20. In an oscillatory pneumatic starter, in combination, a cylinder, a shaft extending therethrough, bearings for said shaft whereby to support the cylinder, a driving gear

35 fixed to one end of said shaft for operative connection with an engine, a sleeve on said shaft within the cylinder, a clutch between the sleeve and shaft adapted to permit the shaft to be moved longitudinally relative

40 to the cylinder whereby to align the driving gear thereon with respect to its connection with the engine shaft, and a pump carried also on said shaft and having its piston operatively connected therewith, said connection being such as to permit relative endwise movement of the shaft.

21. In an oscillatory pneumatic starter, in combination, a cylinder having its body portion formed of a single sheet rolled into circular form, the ends of said sheet being

50 flanged and connected together along their longitudinal edges, a piston for said cylinder and a stationary head carried in said cylinder and extending between the flanged

55 ends of said body portion and supported thereby.

22. In an oscillatory pneumatic starter, in combination, a cylinder having its body portion formed of a single sheet rolled into circular form, the ends of said sheet being

60 flanged and connected together along their longitudinal edges, a piston for said cylinder and a stationary head carried in said cylinder and extending between the flanged

ends of said body portion and supported 65 thereby, and disk shaped end walls for said cylinder clamping against the ends of said stationary head.

23. In a pneumatic starting mechanism, in combination, a cylinder formed of a sheet 70 of metal rolled into circular form with the ends of said sheet outturned into opposing flanges, end walls for the cylinder, a stationary head secured between the flanges of the cylinder in spaced relation to one thereof 75 to provide an outlet, and a piston rotatably mounted in the cylinder and normally contacting with the head, said cylinder being formed with a peripheral inlet opening disposed in radial alignment with the contact- 80 ing faces of the piston and head.

24. In a pneumatic starting mechanism, in combination, a cylinder formed of a sheet of metal rolled into circular form with the ends of said sheet outturned into opposing 85 flanges, spacing means secured between the flanges to hold the latter apart and thereby provide for the escape of air in advance of the piston, end walls for the cylinder, a stationary head fixed between flanges and arranged in the cylinder, and a piston rotatably mounted in the cylinder and normally contacting with the head.

25. In a pneumatic starting mechanism, in combination, a cylinder having its body 95 formed of a single sheet rolled into circular form with the ends of said sheet turned outwardly into opposing flanges, means adjustably connecting the flanges, said cylinder being formed with a seat adjacent each end, 100 a head engaged in each seat and held therein by tightening upon said flange connecting means, each head having a hub extension, a sleeve journaled in the hubs, a piston carried by the sleeve within the cylinder, a shaft 105

passing through the sleeve, a clutch part interposed between the sleeve and shaft and slidably connected to one, a coöperating clutch part threadedly connected to the other of said two last named elements for advancement toward and retraction from the first clutch part, a gear fixed on the shaft for connecting the latter to the shaft of an engine, and means for sliding the first shaft relative to the clutch parts for adjusting the 110 position of the gear.

26. In a pneumatic starter, in combination, a cylinder rolled from sheet metal and formed with longitudinal edge flanges by which the sheet metal is secured in cylinder 120 form, removable heads for the ends of the cylinder held in position by securing the longitudinal flanges together, a pump carried by one head, a piston in the cylinder, a shaft extending through the cylinder for 125 operating the pump, and means connecting the piston to the shaft.

27. In a pneumatic starting mechanism, in

combination, a casing, end walls therefor having bearings, a sleeve-like shaft journaled in the end wall bearings and having a perforated hub extension projecting through one end wall, a piston carried by said shaft for operating with the casing, a second shaft arranged within the first shaft and having an end projecting from the hub extension, a movably supported journal block in which the projecting end of the second shaft is supported, said journal block having a perforated cylindrical flange encircling the hub extension, and a coiled spring for returning the piston to normal position having hooked terminals engaging respectively in the perforations of the hub extension and block flange, said journal block adapted for being turned to vary the tension of the spring.

28. In a pneumatic starting mechanism, in combination, a casing, end walls therefor having bearings, one end wall having an annular flange, a sleeve-like shaft journaled in the end wall bearings and having a perforated hub extension projecting through said specified end wall, a piston carried by said shaft for operating with the casing, a second shaft arranged within the first shaft and having an end projecting from the hub extension, a movably supported journal block in which the projecting end of the second shaft is supported, said journal block having a perforated cylindrical flange encircling the hub extension and telescopically related with the end wall flange, and a coiled spring for returning the piston to normal position

having hooked terminals engaging respectively in the perforations of the hub extension and block flange, said journal block adapted for being turned to vary the tension of the spring, and means detachably securing the telescoped flanges together.

29. In a pneumatic starter, in combination, a cylinder, end walls therefor having hub extensions, a hollow shaft journaled in the latter, a piston carried by the shaft, a driven shaft extending through the hollow shaft and unsupported thereby, means releasably connecting the shafts, and journal bearings for the driven shaft arranged outwardly of the hollow shaft.

30. In a pneumatic starter, in combination, a cylinder, end walls therefor having hub extensions, a hollow shaft journaled in the latter, a piston, a radial series of rods carried by the shaft, headed bolts interposed between the rods and attached to the piston for clamping the rods to the piston beneath the bolt heads, a driven shaft extending through the hollow shaft and unsupported thereby, means releasably connecting the shafts, and journal bearings for the driven shaft arranged outwardly of the hollow shaft.

In testimony whereof I have hereunto set my hand in the presence of two subscribing witnesses.

CLINTON L. WALKER.
